UNITED STATES PATENT OFFICE.

JOHN R. DENNY, OF PIASA, ILLINOIS.

FARM-GATE.

SPECIFICATION forming part of Letters Patent No. 289,998, dated December 11, 1883.

Application filed May 21, 1883. (No model.)

To all whom it may concern:

Be it known that I, JOHN R. DENNY, of Piasa, in the county of Macoupin and State of Illinois, have invented a certain new and useful 5 Improvement in Swinging Gates, of which the following is a full, clear, and exact description, reference being had to the accompanying drawings, forming part of this specification, in which—

10 Figure 1 is a perspective view. Fig. 2 is an enlarged perspective view of the upper hinge and its attachments. Fig. 3 is a similar view of the lower hinge. Fig. 4 is a detail perspective view of the forked bar or rod for holding 15 the gate in its different positions. Fig. 5 is an enlarged perspective view of the part of the lower hinge secured to the post. Fig. 6 is an enlarged top view of the operating-drum. Fig. 7 is a vertical section taken on line 7 7, Fig. 6. Fig. 8 is an enlarged detail view of the front 20 end of the gate. Fig. 9 is a horizontal section taken on line 9 9, Fig. 8; and Fig. 10 is a vertical section of the upper end of one of the side posts.

25 My invention relates to a gate that can be opened either way by a person in a vehicle, on horseback, or on foot; and my invention consists in certain features of novelty hereinafter fully described, and pointed out in the claims.

30 Referring to the drawings, A represents the gate, and B C its posts, which may be made of any suitable construction and from any suitable material or materials. The posts are preferably provided with caps B' C', respectively, 35 as shown.

D represents the latch, pivoted to the gate at D', and having adjustably secured to it above the pivot-point a catch-bar, E, for engaging with the front post, B, as shown in Figs. 8 and 40 9. The catch is held forward to engage with the post when not pulled back by a suitable spring, F, connecting the latch and the gate. (See Fig. 8.)

45 The upper hinge consists of two parts, G H, the part G being secured to the post and the part H to the gate. The part H has a vertical stem, H', which passes up through the part G, and has a grooved drum, I, on its upper end, and it is strengthened or supported laterally by suitable boxes, J K, connecting it

with the gate and post. (See Figs. 1 and 2.) The drum I has a single or a double groove, as desired.

L is a spring-rod connecting the wheel and stem. The wheel is turned to open the gate 55 by means of cords or wires M N, fitting in its groove or grooves and passing around chain-wheels O' P', journaled in the upper ends of side posts, Q R, by means of crank-shafts O P. The outer portions of the cords or wires M N 60 are provided with short lengths of drive-chains M' N', (see Figs. 1 and 10,) that engage the cog-wheels O' P'. By turning either one of the cranks O P the drum will be turned, and its opposite sides, being connected to the gate 65 by wires or cords S T, the gate will be swung open in the direction in which the drum is turned. The crank should be turned, of course, in the direction that will open the gate away from the operator. The cords or wires S T 70 connect with the latch, (see Figs. 1 and 8,) so that the first thing the turning of the drum does is to disengage the catch from the post, allowing the gate to be opened. The spring-rod connecting the drum with the stem of the 75 hinge will allow the drum to turn slightly, (see Fig. 6,) thus operating the latch in advance of the gate, and as soon as the power is removed from the crank the spring will return the drum to its normal position, thus taking all unnecessary strain from the latch and allowing its 80 spring to throw it forward. The wires or cords M N and S T are connected to the drum by bolts U, having nuts U' on their lower ends and eyes U'' on their upper ends, through two 85 of which the ends of the rod L pass. (See Figs. 2, 6, and 7.) The posts Q R are preferably provided with caps Q' R', to protect the chain-wheels O P from rain, &c., and these posts, as well as the others, are held from sagging by guy rods or wires V, secured to the posts and to objects in the ground, and kept taut by adjustable brace-sticks V', placed between them and the posts, as shown.

W W represent posts for the gate to open 95 against, and they may be provided with catches W', to hold the gate open.

X Y represent the parts of the lower hinge, X being the part connected to the gate, and Y the part connected to the post. The part X 100

has an eye, X', that fits over a stem, Y', on the part Y, and above the point of bearing the stem Y' is made square. (See Fig. 5.)

Z represents a bar connected to the lower end of the latch by its forward end, and having its back end, Z', forked, (see Fig. 4,) to engage the square portion of the stem Y'. (See Fig. 3.) The back end of this bar passes through the part X of the hinge, and is guided by lugs X². (See Fig. 3.) The object of this bar is to form an automatic device to hold the gate open or closed should the catches fail to operate or should they be dispensed with. The forward movement of the upper end of the latch engages the bar with the stem, (when the gate is open or closed,) and when the upper part of the latch is moved back, as described, the bar is disengaged from the stem, so that the gate can be operated. This device

20 may be used by itself or in connection with the catches, to hold the gate closed and open.

The latch D terminates in a handle, as shown, so that it can be operated by hand when desired, the spring on the drum having relieved 25 the latch of all unnecessary strain.

The box J may be dispensed with, if desired. The brace-sticks V may be kept from falling out, should the guy-wires V become loose, by small sticks of wood secured to the posts, 30 or by any suitable means.

There may be a cross-bar or large ring placed between the wires M N and the chains M' N', which would come against the posts and limit 35 the turning of the cranks, so that they cannot be turned too far by an inexperienced person.

I claim as my invention—

1. In a swinging gate, the combination of a suitable stem, a drum mounted thereon, a spring-rod to connect the drum to the stem, 40 wires or cords connecting the drum to the gate,

and wires or cords for turning the drum, as set forth.

2. The combination of gate A, post C, the upper hinge consisting of two parts, H G, the part H having a stem, H', drum I on the stem 45 H', and connected therewith by a spring-rod, L, wires M N, connected to the drum, and provided with suitable means for operating them, and wires S T, connecting the drum with the latch of the gate, substantially as and for the 50 purpose set forth.

3. The combination of gate A, the lower hinge consisting of two parts, X Y, the part Y having a round stem, Y', formed with a squared portion, and the forked bar Z, connected to the lower part of the latch and engaging the squared portion of the stem Y' when the gate is opened or closed, substantially as and for the purpose set forth. 55

4. The combination of gate A, the lower hinge consisting of parts X Y, the part X having an eye, X', and lugs X², and the part Y having a round stem, Y', formed with a squared portion, and the forked bar Z, to engage the squared portion, all substantially as shown and described, for the purpose set forth. 60

5. In a swinging gate, the combination of the stem H', a drum, I, mounted on the stem, a spring-rod to connect the drum to the stem, wires connecting the drum to the gate, wires 70 M N, extending from the drum, having chains connecting their outer ends, and posts having wheels with crank-shafts, to work the chains, as set forth.

JOHN R. DENNY.

In presence of—

L. H. CHAPIN,
DANIEL D. GORDELL,
C. H. NUTTER.
